Harlow M. Davis

UNITED STATES PATENT OFFICE

ARTHUR S. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING INSERTING MACHINE

Application filed July 6, 1931. Serial No. 548,736.

This invention relates to machines for use in the manufacture of boots and shoes and is illustrated herein as embodied in a machine having a gage particularly adapted 5 for use in attaching shank stiffeners to boots and shoes.

In the manufacture of boots and shoes it is customary to attach shank stiffeners to the insoles of the boots and shoes prior to the 10 laying of the outsoles by means of fastenings which pass through the stiffeners and through the insoles. Metallic shank stiffeners are provided with apertures for the reception of the fastenings and when the fastenings are driven by the use of fastening inserting machines, 15 it is important that the apertures in the shank pieces be accurately alined with the fastening inserting means of the machines. When applying shank stiffeners of the type 20 described and claimed in a copending application, Serial No. 530,914, filed April 17, 1931, in the names of Leroy W. Rollins and Arthur S. Johnson, in which the sides of the fastening receiving apertures are formed to provide 25 deflecting surfaces for the legs of the fastenings, it becomes increasingly important that the apertures be accurately alined with the fastening inserting means of the machine 30 to insure that the legs of the fastenings will be properly deflected and be caused to curl without penetrating through to the other surface of the insole.

One object of this invention is to provide an improved device for positioning a member 35 having fastening receiving apertures relatively to the fastening inserting means of a machine whereby the fastening receiving apertures are accurately alined with the fastening inserting means.

40 In accordance with this object one feature of this invention resides in a fastening inserting machine having fastening inserting means, a member adapted to position a work piece longitudinally relatively to the fastening inserting means, and means constructed and arranged to position the work piece 45 transversely relatively to the fastening inserting means whereby fastening receiving apertures in the work piece are brought into 50 alinement with the fastening inserting

means. As herein illustrated, the means for positioning the work piece are mounted on a bracket secured to the throat piece of a fastening inserting machine, the free end of the bracket having adjustably secured thereto a resilient spring-like member having an end portion extending at an angle to the main portion of the member for engaging the end of the stiffener to position the stiffener longitudinally, and secured to the 55 bracket adjacent to the throat piece are a pair of members which are adjustable toward and from each other to accommodate shank stiffeners of different widths, these members being adapted to position the shank stiffener 60 transversely.

Other objects and features of the invention will appear from the following description and claims when considered in connection with the accompanying drawing, in 70 which

Fig. 1 is a perspective view of one embodiment of the invention;

Fig. 2 is a sectional view taken along the line II-II of Fig. 3;

Fig. 3 is a longitudinal sectional view taken along the line III-III of Fig. 2; and

Fig. 4 is a perspective view of another embodiment of the invention.

The invention will be described by way of example as applied to a fastening inserting machine of the type disclosed in United States Letters Patent No. 1,011,592, granted Dec. 12, 1911, on application of Wilfred J. Drey, to which reference may be had for a 80 complete description of the parts not fully described herein. The machine comprises a nozzle or throat piece 10 through which staples pass for insertion into the work, the staples being inserted into the work by a driver 12 which is reciprocated upwardly and downwardly in suitable guides in the machine frame. The throat piece 10 is formed in two parts 14 and 16 which are secured together by means of screws or studs 18. 85

The shank piece or stiffener 20 disclosed in the above-mentioned application is provided with fastening receiving apertures 22 having their walls formed to provide deflecting surfaces for the legs of a staple 24 90

so that when the staple is inserted through the apertures 22 by the driver 12 the legs of the staple are curled inwardly and clench beneath the bar of the staple in such a manner as most effectively to resist displacement and thus securely to hold the stiffener in place on an insole 26. As shown in Fig. 3, the apertures 22 may be spaced longitudinally of a narrow stiffener, or, as shown in Fig. 10 4, the apertures may be spaced transversely of a wide stiffener.

The gage for positioning the stiffener 20 in proper position beneath the driver 12 with the fastening receiving apertures 22 in alignment with the driver bar 12 includes a bracket 28 which has an extension 30 at one end through which pass the screws 18. The bracket is rigidly held in place on the throat piece by means of nuts 32 which are threaded on the screws 18. The end 34 of the bracket is provided with a downwardly extending portion 36 provided with threaded holes which receive cap screws 38. An end gage 40 for the stiffener is provided with a slot 42 at 25 one end through which the screws 38 pass adjustably to secure the end gage to the bracket 28. The end gage is formed of spring steel and, as shown in Fig. 3, is provided with an angular portion 43 against which the end 30 of the stiffener 20 is placed. The angular portion 43 is normally located below the plane of the lower end of the throat piece 10 and is adapted to yield upwardly when the insole 26 is pressed thereagainst.

35 The end of the bracket adjacent to the throat piece 10 is provided with an enlarged portion 44 which is shaped at its lower surface to provide a guideway for a pair of lateral gages 46. These lateral gages are each 40 provided at their upper ends with extensions 48 having oppositely threaded holes. An adjusting screw 50 having oppositely threaded portions is passed through the oppositely threaded holes in the extensions 48 and rotation of the screw 50 will cause the gages 46 to be moved toward and from one another to accommodate shank stiffeners of 45 different widths. The adjusting screw 50 has a reduced portion substantially centrally of 50 its length into which fits a U-shaped retaining member 52 which prevents axial displacement of the screw relatively to the bracket 28. The retaining member is secured to the bracket 28 by means of a cap screw 54 which passes 55 through an extension formed as a part of the retaining member 52.

The construction described above is adapted to be used in locating the fastening receiving apertures of a shank piece in alignment with the fastening inserting means of the machine when the apertures are spaced longitudinally of the stiffener. When using relatively wide shank stiffeners it is sometimes desirable to position the fastening receiving apertures transversely of the shank.

The construction shown in Fig. 4 is particularly adapted for use in alining transversely spaced apertures with respect to the fastening inserting means of the machine. The modification shown in Fig. 4 is substantially the same as that shown in Fig. 1 except that the bracket 28 is not provided with an extension 30 for securing the bracket to the throat piece 10. The enlarged end portion 44 of the bracket is provided with holes through which the screws 18 pass and the nuts 32 secure the brackets in place on the throat piece 10. The bracket 28 shown in Fig. 4 is secured in position at right angles to the position shown in Fig. 1 and when a shank stiffener having transversely spaced apertures is being used the end and lateral gages 40 and 46 will properly position the apertures with respect to the fastening inserting means.

While the parts of the device have been described in detail, it may be well to summarize briefly the operation of the device. The operator places a shank stiffener in proper position on an insole and, while holding the shank stiffener in position, places one end of the shank stiffener against the downturned portion 43 of the gage 40 in a plane below the working position, thus positioning the shank piece longitudinally with respect to the driver 12. Then the work, due to the resiliency of the member 40, is directed between the side or lateral gages 46 which have been adjusted to the proper width. These engage the sides of the stiffener and locate it transversely. When the shank stiffener has been positioned, the operator treads the machine, causing the driver bar to move downwardly and insert a staple through the stiffener. The legs of the staple engage and are deflected by the walls of the apertures and are clenched beneath the stiffener. The shank stiffener and insole may then be turned end for end and another staple may be inserted in apertures in the other end of the stiffener.

Having thus described my invention, what I claim as new and desire to secure by Letters Patent of the United States is:

1. In a fastening-inserting machine, fastening-inserting means, an adjustable resilient member adapted to position a work piece longitudinally relatively to the inserting means and located below the plane in which fastenings are to be inserted in the work piece, and means located substantially in the plane in which the fastenings are to be inserted in the work constructed and arranged to position the work piece transversely relatively to the fastening-inserting means, whereby fastening-receiving apertures in the work piece are brought into alinement with the fastening-inserting means.

2. In a fastening-inserting machine, a throat piece, fastening-inserting means re-

ciprocable in said throat piece, a bracket secured to said throat piece, yielding means adjustably secured to the free end of said bracket and extending substantially below said throat piece for positioning a shoe part longitudinally of a shoe, and means adjustably secured to the bracket for positioning the shoe part transversely of the shoe whereby fastening-receiving holes in the work piece are brought into alinement with the fastening-inserting means.

3. In a fastening-inserting machine, a throat piece, fastening-inserting means in said throat piece, a bracket secured to said throat piece, means secured to the bracket for positioning a work piece having fastening-inserting holes therein, said means being constructed and arranged to position the work piece transversely relatively to the inserting means, and a resilient member secured to the bracket and having an angular portion adapted to engage the end of the work piece to position the work piece longitudinally relatively to the inserting means whereby the fastening-receiving holes in the work piece are alined with the fastening-inserting means.

4. In a fastening-receiving machine, a throat piece, a fastening-inserting driver reciprocable in said throat piece, a bracket secured to the throat piece, means for positioning a work piece transversely relatively to the driver, said positioning means being located in substantially the plane of the lower end of the throat piece, and means for positioning the work piece longitudinally, said last-mentioned means extending substantially below the general plane of said first-mentioned means and being constructed and arranged to yield upwardly under pressure applied to the work by the operator.

5. In a fastening-receiving machine, a throat piece, a fastening-inserting driver reciprocable in said throat piece, a pair of members constructed and arranged to position a work piece transversely relatively to the driver, said members being located in substantially the same plane as the lower end of the throat, and means extending below said members and adapted to yield to locate the work piece longitudinally.

6. In a fastening-inserting machine, a throat piece, a fastening-inserting driver reciprocable in said throat piece, a bracket secured to said throat piece, a gage adjustably secured to the bracket and having an end portion adapted to yield upwardly upon the application of pressure thereto, said end gage operating to locate a work piece longitudinally, and a pair of edge gages mounted in said bracket for movement toward and from each other to accommodate work pieces of different widths, said edge gages operating to locate the work pieces transversely.

7. In a machine for inserting fastenings in a work piece having fastening-receiving

apertures located therein, fastening-inserting means, means for locating the fastening-receiving apertures longitudinally relatively to the fastening-inserting means, said locating means being constructed and arranged to yield vertically to permit the work piece to be moved into engagement with the fastening inserting means, and adjustable means for positioning the work piece transversely whereby the fastening-receiving apertures in the work piece are brought into alinement with the fastening-inserting means of the machine.

8. In a machine for inserting staples in a work piece having fastening-receiving apertures located therein, staple-inserting means, an end gage adjustable in a plane below the fastening inserting means and yieldable toward and away from said inserting means, said gage being adapted to engage the end of a work piece to position the work piece longitudinally, and a pair of edge gages for positioning the work piece transversely whereby the fastening-receiving apertures in the work piece are brought into alinement with the staple-inserting means.

9. In a machine for inserting staples in a work piece having fastening-receiving apertures formed therein, the walls of said apertures being formed to deflect the legs of a staple to cause the legs of the staple to be clenched beneath the work piece, means for locating the work piece longitudinally, said means being normally located in a plane substantially below the staple inserting position and adapted to be displaced to permit the work to be brought into fastening inserting position and means for locating the work piece transversely whereby the fastening-receiving apertures are brought into alinement with the legs of the staple to be inserted in the work.

10. In a machine for inserting fastenings in a shank piece having fastening-receiving apertures formed therein, a throat, a fastening-inserting driver reciprocable in said throat, means normally located in a plane below the end of the throat and arranged to be displaced by the work into the plane of the lower end of the throat to locate the shank piece longitudinally relatively to the driver, and a pair of edge gages for engaging the edges of the shank piece to locate the shank piece transversely relatively to the driver whereby the fastening-receiving apertures are brought into alinement with the line of drive of the fastenings.

11. In a fastening-inserting machine, a throat piece, a fastening-inserting driver in said throat, a resilient member normally located in a plane below said throat piece and adapted when engaged by a work piece to be moved substantially into the plane of the lower end of the throat to position a shank piece longitudinally relatively to the driver,

and means constructed and arranged to position the work piece transversely relatively to the driver whereby fastening-receiving apertures in the work piece are brought into alignment with the fastening-inserting driver.

In testimony whereof I have signed my name to this specification.

ARTHUR S. JOHNSON.
